MACHINE FOR PRODUCING WET ADHESIVE TAPE STRIPS

Arthur L. Clements and Norman R. Easter,
Evanston, Ill., assignors to Dry-Zero Corporation, Chicago, Ill., a corporation of Illinois

Application November 27, 1935, Serial No. 51,811

3 Claims. (Cl. 91—14.5)

This invention relates to improvements in machines for application of wet adhesive to strips of paper or similar material of the type used for securing package wrappings and the like. More particularly, the machine of our present invention is especially designed for the use of silicate of soda as adhesive material, which has particularly advantageous characteristics as compared to adhesive gums, but which has heretofore been extremely difficult to handle in adhesive-applying machinery. Various machines have heretofore been developed for applying adhesive to strips, tape or sheets, but so far as we are aware, they have all operated on the principle of pulling the wet tape through the adhesive-applying mechanism by means of drag rolls or similar devices. As a result, particularly notable with silicate of soda, the adhesive tends to build up on the pulling means, requiring frequent shut-downs for cleaning the machine, and at the same time adversely affecting the film of adhesive.

In carrying out our invention, we have provided an improved form of machine and method of operating the same whereby successive strips of paper or similar fabric may, at the will of the operator, be fed to a wet adhesive-applying mechanism, and be automatically cut off in predetermined lengths, each successive strip portion being propelled or "shot" with sufficient force to carry it through the adhesive-applying mechanism and delivered in wet condition to the hand of the operator ready for immediate application as required. The automatic cut-off mechanism is arranged to sever each individual strip as it passes through the adhesive-applying mechanism, but the arrangement is such that the strip, after being severed from the propelling mechanism, will complete its movement through the adhesive-applying mechanism and be delivered to the hand of the operator without the assistance of any pulling mechanism.

We also provide means for readily adjusting the length of successive strips to be delivered from the machine.

Other objects and novel features of the invention will appear from time to time as the following description proceeds:

The invention may best be understood by reference to the accompanying drawing, in which the single figure illustrates in diagrammatic form a machine embodying our invention.

Referring now to details of the embodiment of our invention illustrated in the drawing, the machine consists primarily of two main elements, namely, an intermittent tape feeding device indi-

cated generally by the numeral 10, and an adhesive-applying mechanism indicated generally by the numeral 11.

The tape-shooting device shown herein consists of a tape driving roller 15 on shaft 16 driven by pinion 17, meshed with an internal gear 18 of wheel 19. Said wheel has a ratchet member 20 carried therewith, and said wheel with its ratchet are loosely mounted on a shaft 21. An operating lever arm 22 is also loosely mounted on the shaft 21 and carries a spring-pressed pawl 23 adapted to engage the ratchet 20 carried by the wheel 19 so as to rotate said wheel when the lever 22 is moved in a clockwise direction. Said pawl and ratchet thus form, in effect, a one-way overrunning clutch. A compression roller 14 is mounted opposite to the feed roller 15 so as to grip the strip of paper 13 therebetween. The paper strip 13 is supplied from a roll 13^a suitably mounted on the frame 12 and passing over straightening rollers 13^b and 13^c to the feed roller 15.

It will be understood that the parts of the tape-shooting mechanism above described are similar to those heretofore used in hand-operated tape-shooting devices for supplying strips of tape already treated with dry adhesive, but such tape-shooting machines are usually actuated by manual operation of the lever 22. We do not, therefore, claim any novelty in the tape-shooting machine per se, but only in combination with other parts of the machine whereby novel results are attained, as will presently be described.

Referring now to the power actuated drive means, we provide a motor 25 mounted on the frame 12 and connected to a drive shaft 26 through suitable gear reduction mechanism, such as a plurality of sprockets or pulleys 27, 28, 29, 30, 31, and 32, each successive pair of sprockets or pulleys being connected by chains or belts 27^a, 29^a, and 31^a.

An eccentric 35 is also mounted on the shaft 26 and is adapted to be intermittently connected to the shaft 26 by means of a single revolution clutch indicated generally at 36, which clutch may be of any suitable construction, and controlled through a trip lever 37 extending in a position to be actuated by the operator. In the form shown, the trip lever 37 has a foot pedal 37^a projecting at the front of the machine near its base.

The eccentric 35 is connected by link 38 to a lever 39 pivoted to the frame at 39^a and extending in a generally horizontal position toward the front of the machine. The forward end of the lever 39 is connected to the arm 22 of the tape-shooting device by a link 40. Means for adjusting the

length of the severed tape sections is afforded by providing a series of holes 38^a in the lever 39, in which holes the eccentric link 38 may be selectively connected. This adjustment controls the arc of movement of the lever 22, and affords considerable variation in the "throw" of the tape-shooting mechanism, so as to produce tape sections of different lengths, as desired.

The single revolution clutch 36 includes a driv-
10 en member 41 which carries thereon a boss 42 adapted to engage and depress a bar 43 at a pre-
determined point of revolution. Said bar 43 is pivoted at one end on pin 44. The outer or free
15 end of said bar is connected by an upwardly ex-
tending link 45 to a knife 46 movable in an up-
right guide 47 across the path of the tape 13 as it
is fed from the tape-shooting device through
upper and lower guide members 48 and 49. Said
boss 42 is so positioned on said member 41 that
20 it depresses said bar 43 and so actuates said knife
46, substantially at the end of the movement of
said described tape-shooting device.

Referring now to details of the adhesive-ap-
plying mechanism, the same includes a roller 50
25 mounted above an adhesive receptacle 51 at the
front of the frame 12 and having means for sup-
plying adhesive thereto as by an intermediate
feed roll 52 having its lower portion adapted to
rotate in the adhesive 53 of the receptacle 51
30 and arranged to contact the under surface of
the applying roll 50. In the preferred form
shown, both the adhesive-applying roll 50 and the
feed roll 52 are driven by power, as through
sprockets or pulleys 50^a and 52^a and chains or
35 belts 54 and 55 suitably connected to the motor
25 as by a sprocket or pulley 56 connected to the
intermediate drive member 28 heretofore de-
scribed as part of the drive connection to the
tape-shooting drive mechanism 26. Suitable
40 guide means for the tape is provided for lead-
ing the tape directly from the cutting knife 46
to the adhesive-applying roll 50, herein consist-
ing of an upper guide 58 and a lower guide 59.
As the leading edge of each successive strip is
45 propelled through these guides, it passes beneath
a light floating roller 60. The forward end of the
lower guide 59 is curved upwardly beyond the
last named roller so as to direct the tape in a
plane generally tangential to the surface of the
50 adhesive-applying roll 50 and beneath a float-
ing presser 61. When the leading edge of the
strip touches the rapidly revolving adhesive roll
50, the strip comes in contact with the adhesive
on said roll and tends to follow the curvature of
55 the latter until peeled off by one or more strip-
per fingers 62. Said strippers are provided with
knife edges so as to prevent any disturbance of
the film of adhesive applied to the under surface
of the strip.

60 Having described the several parts of the ma-
chine together with their drive connections, the
essential features whereby proper coaction of the
parts is obtained may now be pointed out. It
will be observed that the speed of the feed roll
65 15 of the tape-shooting mechanism is given rapid
acceleration through the quick-throw lever 22
and the internal gear wheel 17 so that the strip is
propelled from the tape-shooting mechanism at
a relatively high speed, and with considerable im-
petus toward the adhesive-applying roll 50.

60 The roll 50 is constantly driven at a peripheral
speed which is slightly less than the maximum
speed of the feed roll 15. Consequently, the
speed of movement of the tape will be somewhat
70 retarded as it passes over the adhesive-applying

roll, particularly when the feed roll reaches its maximum speed. It will be noted, however, that the guides 50 and 59 beyond the cut-off knife 56 are spaced apart and are also flared at their opening ends so as to permit the strip to crumple or corrugate longitudinally an amount sufficient to compensate for the momentary greater speed of the feed roll.

The operation of the cut-off knife 46 is timed by positioning the pin 42 on clutch member 41 so as to actuate the knife at the instant before the forward motion of the tape ceases. This action permits the last portion of each tape section to continue its movement at substantially uniform speed over the adhesive-applying roll. If cut off too soon, the following portion of the tape will tend to jam against the knife, while if not cut off soon enough, the movement of the tape over the adhesive roll may tend to be retarded so as to affect the even distribution of adhesive on the strip.

The adhesive roll is particularly effective in continuing the forward movement of each strip after it has been cut off by the knife 46. The arrangement is such, therefore, that the adhesive roll 50 serves to stabilize the movement of each strip through the adhesive-applying mechanism at a substantially constant speed so as to produce an adhesive film of uniform thickness thereon.

Although we have illustrated and described one particular embodiment of our invention, it will be understood that we do not wish to be limited to the exact construction shown and described, but that various changes and modifications may be made without departing from the spirit and scope of our invention as defined in the appended claims.

We claim:

1. In a device of the character described, the 40 combination of an adhesive-applying roll and
means for supplying liquid adhesive to the sur-
face thereof, a tape-shooting device including a
feed roll adjacent said adhesive-applying roll,
means for driving said adhesive roll at substan- 45 tially uniform speed, and means for intermit-
tently driving said feed roll at a peripheral
speed slightly greater than the adhesive roll
including a quick-throw lever and a one-way
clutch, and cut-off means interposed between 50
said tape-shooting device and said adhesive roll
operated in timed relation with said tape-shoot-
ing device to sever a tape strip fed by the latter
in predetermined lengths.

2. In a device of the character described, the 55 combination of an adhesive-applying roll and
means for supplying liquid adhesive to the sur-
face thereof, a tape-shooting device including a
feed roll adjacent said adhesive-applying roll,
means for driving said adhesive roll at sub- 60 stantially uniform speed, means for intermittently
driving said feed roll at a peripheral speed slight-
ly greater than the adhesive roll, cut-off means
operated in timed relation with said tape-shoot-
ing device for severing a tape strip fed by the 65 latter in predetermined lengths, guide means
arranged to lead a tape strip under propulsion
from said tape-shooting device to said adhesive-
applying roll, said guide means beyond said cut-
off means being arranged to permit limited 70
crumpling of the tape to compensate for momen-
tary excess of speed of said tape propelled from
said tape-shooting device over the peripheral
speed of the adhesive-applying roll.

3. In a device of the character described, the 75

5 combination of an adhesive-applying roll and means for supplying liquid adhesive to the surface thereof, a tape shooting device adjacent said adhesive roll including a feed roll arranged to feed a tape strip to said adhesive-applying roll, a motor, drive connections between said motor and said adhesive-applying roll for driving the latter at a substantially constant speed, other driving connections between said motor and said feed roll including a single revolution clutch and means for engaging said clutch at the will of the 10 operator, cut-off means operated in timed rela-

tion with said single revolution clutch for severing a tape strip at the completion of each successive operation of said feed roll, said drive connections for said feed roll also including a lever interposed between said feed roll and said single revolution clutch, and means for adjusting at will the effective length of said lever so as to vary the lengths of tape strips fed by said feed roll.
